US00D979842S

(12) **United States Design Patent** (10) **Patent No.:** **US D979,842 S**
(45) **Date of Patent:** **** Feb. 28, 2023**

(54) **ELECTRIC DRY SHAVER**

(71) Applicant: **Braun GmbH**, Kronberg (DE)
(72) Inventors: **Philipp Goeder**, Frankfurt (DE);
Gregor Ptak, Frankfurt (DE);
Bernhard Sikora, Kelkheim (DE);
Wolfgang Stegmann, Frankfurt (DE)
(73) Assignee: **Braun GmbH**, Kronberg (DE)

(**) Term: **15 Years**

(21) Appl. No.: **29/781,564**

(22) Filed: **Apr. 30, 2021**

Related U.S. Application Data

(62) Division of application No. 29/709,111, filed on Oct. 11, 2019, now Pat. No. Des. 921,985, which is a division of application No. 29/598,471, filed on Mar. 27, 2017, now Pat. No. Des. 868,377.

CLAIM

The ornamental design for an electric dry shaver, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an electric dry shaver;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof.

FIG. 8 is a perspective view of a second embodiment of an electric dry shaver;

FIG. 9 is a front view thereof;

FIG. 10 is a right side view thereof;

FIG. 11 is a rear view thereof;

FIG. 12 is a left side view thereof;

FIG. 13 is a top plan view thereof; and,

FIG. 14 is a bottom view thereof.
